United States Patent Office.

GEORGE W. WOOD, OF NEW YORK, N. Y., ASSIGNOR TO JOSEPH W. KENDALL, OF PHILADELPHIA, PENNSYLVANIA.

Letters Patent No. 102,351, dated April 26, 1870.

IMPROVEMENT IN EAR-BRUSHES.

The Schedule referred to in these Letters Patent and making part of the same.

To all whom it may concern:

Be it known that I, GEORGE W. WOOD, of New York, of New York county, in the State of New York, have invented a new and useful Improved Ear-Brush; and I do hereby declare that the following is a full and exact description thereof, reference being had to the accompanying drawings making part of this application.

Previous to my invention, what is known in surgery as a "probang" has been used to cleanse and probe the ear, and a merchantable and more desirable article for common use as an ear-brush or cleanser is now manufactured and sold, known as the "aurilave" or ear-brush, such as described in Letters Patent granted to G. H. M. F. Lovell, and dated July 27, 1869.

In the ordinary "probang," a piece of sponge is simply secured in any desirable manner to one end of a suitable stem, generally of a flexible nature, while in the ear-brush manufactured under the Letters Patent referred to, the sponge is fastened to one end of a rigid handle or stem made of wood, ivory, or other suitable material, and a portion of the said stem or handle and part of the sponge (where the sponge is secured to the stem) are enveloped by a rubber tube, which covers and protects the fastening, and forms a finish.

In both the instruments mentioned, adapted to wash or cleanse the ear, the sponge or other material constituting the brush portion, or that part which is wet and used to wash with, is always uncovered or exposed, which is obviously an objection.

It will be understood that an ear-brush as heretofore made is liable to have its sponge get dirty when not in use, and that, as a toilet article, it is often inconvenient to put away or carry after use with the wet portion exposed.

My invention has for its main object to overcome the objections which exist in the ear-brush or instrument for cleansing the ear as heretofore made, with its sponge portion unprotected, or always uncovered, and provide a more desirable and better article; and to this end,

My invention consists in providing an ear-brush or instrument for cleansing the ear with a movable shield or protector, which can, at pleasure, be made to enclose or cover and protect the sponge, or that part which is wetted to wash with, as will be hereinafter more fully explained; and

My invention further consists in certain improvements in the construction and arrangement of the parts of an ear-brush, hereinafter more fully described.

To enable those skilled in the art to make and use my invention, I will proceed to describe it more fully, referring by letters to the accompanying drawings, in which—

Figure 1 is an elevation of one of my improved ear-brushes;

Figure 2 is a longitudinal section of the same;

Figure 3, a similar section with the sponge covered; and

Figure 4, detail detached views.

In the several figures, the same parts are designated by same letters of reference.

A is the handle or stem of the brush;

B, the sponge or brush part; and

C, the shield or protector.

The handle A may be made of ivory, wood, hard rubber, or other suitable material, of any desired shape and size. I propose to make it about the size and shape shown. It is formed with a screw-thread, at d, and with a teat or projecting end, at e, to which latter the sponge B is secured by a thread wrapping, as clearly seen at fig. 3.

The teat e may have a hole in it, to facilitate the securing of the thread wrapper and sponge.

The sponge B is secured to the teat e in such a manner that the sponge and wrapper shall be about flush with the extreme diameter of the threaded portion d, so that, when the shield C is screwed up over it, its thread will take into, or form an artificial thread in, the sponge and wrapper, the shield coming up against the body of the sponge, covering the wrapper, and forming a finish, as seen at fig. 1.

At fig. 1, the brush is seen as when in use, while at fig. 3 it is shown with the shield C screwed up, so as to entirely cover over the sponge B.

The threaded portion d is long enough to hold the shield C when screwed clear up, as seen at fig. 3, while the plain portion of the handle is made of such a diameter and shape as to permit said shield to be screwed back sufficiently far to allow of the wrapping of the sponge, to secure it in the first place, or remove and renew it.

The general application to use of my improved ear-brush is, of course, about the same as that of the other ear-brushes referred to, and the general advantages of its use need not be alluded to particularly here.

It will be seen that, by making the brush, as described, with the movable shield or protector-tube C, not only is the instrument, when adjusted for use, simple, durable, and finished in appearance, but it is also capable of having the brush or sponge squeezed and covered over, to protect it from dirt, and render the article convenient to carry in the pocket or elsewhere.

Although I propose to make the handle with the teat portion e of less diameter than the threaded part d, and secure the sponge as described, it will be understood that the main feature of my invention—the

movable shield or protector—may be used without this peculiar method of construction; and it will be understood that, in lieu of the screw-shield or tube C, arranged and operating as described, the sponge protector may be differently made and arranged, the gist of this part of my invention consisting in the idea of providing the brush with a suitable movable or removable part adapted to cover the sponge when not in use. But I deem the method of construction and the adaptation of shield shown and described as being the best.

Having explained my invention so that those skilled in the art can make and use my improved ear-brush,

What I claim as new and desire to secure by Letters Patent, is—

1. An ear-brush provided with a suitable shield or protector, which may, at pleasure, be made to cover the sponge portion, substantially as set forth.

2. The shouldered perforated teat, in combination with the sponge and sleeve, substantially as and for the purposes set forth.

In testimony whereof I have hereunto set my hand and seal this 9th day of March, 1870.
